UNITED STATES PATENT OFFICE.

ROBERT W. SCOTT, OF BOSTON, MASSACHUSETTS, ASSIGNOR TO GENERAL KNIT FABRIC COMPANY, OF UTICA, NEW YORK, A CORPORATION OF NEW YORK.

ART OF KNITTING FABRICS.

1,093,359

Specification of Letters Patent. Patented Apr. 14, 1914.

Application filed June 29, 1912. Serial No. 796,885.

To all whom it may concern:

Be it known that I, ROBERT W. SCOTT, a citizen of the United States, and resident of Boston, in the county of Suffolk and State 5 of Massachusetts, have invented a new and useful Art of Knitting Fabrics Having Long and Short Loops, of which the following is a specification.

My invention relates to a method of knitting, which may be practised by hand or upon any of a great variety of machines, such for instance as the machines shown in my copending applications filed July 15, 1909, Serial Number 507,779 (Letters Patent No. 1,034,521, dated August 6, 1912) and filed June 28, 1911, Serial Number 635,880, (Letters Patent No. 1,063,743, dated June 3, 1913) although it will be understood that my present invention is independent of any 20 particular machine, or of the genus of machines of which those shown in said applications are particular species, residing rather in a certain order of operations to be performed upon the component yarn or yarns, 25 during the making of an ordinary knit web, to vary the structure of the web, for instance in such a manner as to produce the fabric upon which was granted my Patent Number 928,221, dated July 13, 1909, which fabric is 30 a product of each of the forms of the said machines disclosed in said applications. It will further be evident that said patented fabric may be made by many different procedures, such as the device of alternately 35 drawing long and short loops by long and short draft needles, in the new or last-formed courses, as disclosed in said patent, and that my present invention relates to an improved and different art of accomplishing 40 the same result, which I will proceed to describe in detail, and then point out in the claims.

In the accompanying drawings Figures 1 to 6 are views of the back side of a fabric 45 resulting from the steps taken in the practice of my invention, showing in diagram the successive stages in the making thereof.

Fig. 1 shows a course *a* of plain fabric knit in successive wales 1, 2, 3, 4, 5, 6, 7, and 8. 50 The order of the numerals may represent the order in which the loops of the course were formed, but it is not essential to the practice of my invention that the loops should be so formed, as in some cases where my in-

vention is to be carried out on certain varieties of straight or flat-bed knitting machines, the loops of a course may be formed simultaneously, except as hereinafter specified: The course *a* is of normal plain fabric all of the loops of which are of the same length. I 55 proceed to form thereupon a succeeding section of fabric having alternate long and short loops by first forming a course *b* which is interknitted with the course *a* at each of the wales. If knitting needles are the instruments employed to form said course *b*, Fig. 1 may be taken as representing the result at a time prior to the casting therefrom of any of the loops of said course *b*; but it will be understood that if said instruments 60 are the needles of an independent needle machine, it is within the scope of my invention to form the loops of the course *b*, and other following courses successively in one wale after another. In order to produce the systematic elongation in course *b* of the loops occupying the even numbered wales, I now proceed to form a third course *c* which is 65 drawn through the loops of the course *b* in the odd numbered wales only. The formation of this course *c* may be successive, in the direction of wale 1 to wale 8. It is essential however that no loop in course *c* shall at this time be formed in the even numbered wales, 70 in order to permit the next step in the operation, which consists in casting the loops of the course *b*, in the odd numbered wales only, from the instruments upon which they were formed on to the neck of the loops of course *c*. The purpose of this operation is 75 to free the loops in recurrent wales, for instance the loops *x* in the odd numbered wales, of the course *b*, to permit the withdrawal from them of some of their yarn, in order to enlarge the intervening or neighboring loops *y* in said course *b*, as for instance in the even numbered wales. 80

A convenient method of performing the steps above outlined is to feed the yarn for the course *c* to all of the needles or other instruments, and then to operate only those instruments which produce the wales of loops, in this course the odd numbered wales, containing that loop which is thereafter to become a short loop *s* in the next preceding 100 course *b*. The instruments for knitting the even numbered wales (by which it will be understood that I merely refer to the re-

maining wales of the fabric, since it is evident that the shorter stitches may be made in groups, or in irregular alternations of wales) are now operated to draw upon the 5 yarn loop in the course *b*, which has not yet been cast from them, in order to take more yarn into the loop *y* in the course *b* at the expense of the neighboring loops *x*. As one group only of many different means capable 10 of performing this step in the operation, any of the devices disclosed in my machine applications Serial Nos. 507,779 and 635,880, may be employed, as for instance those devices for lifting some of the independent 15 needles partly out of the grooves which they occupy in their carrier. The special formation of the course *b* is now complete, as shown in Fig. 3, and it will be noticed that in the steps of the method outlined said 20 course was formed by first drawing its individual loops to a normal and even length, simultaneously or successively, in each wale; that thereafter a second course *c* was formed on some only of the loops of the course *b* 25 and the corresponding loops of the course *b* were cast off in said wales to free them from the instruments on which they were formed, that thereafter the remaining loops *y* of the course *b*, were drawn upon, prior to knitting 30 through them, or simultaneously with the knitting through them, of the remaining loops of the course *c*, to elongate the stitches *y* of the previous course *b* at the expense of the stitches *x* of the same course. 35 Fig. 3 shows the state of the particular fabric chosen for the purpose of illustration after the operation of enlarging the loops in the course *b* by drawing upon them in the direction of the arrows in Fig. 2 has been 40 carried out. Fig. 4 shows the appearance of the course *c* after the operation of the instruments at the even numbered wales to draw or knit the loops of the course *c* through the now enlarged loops of the 45 course *b*.

So far as described the operation has resulted in one course having alternate long and short loops. I may permit the course then following said tight and loose course 50 to remain normal, or I may repeat the operation with respect to the same wales as were affected in the case of the course *b*; but, I prefer to again carry out the operation with respect to the course *c*, in a different order 55 of wales, to stagger or alternate the occurrence of the enlarged loops as disclosed in my fabric Patent No. 928,221 referred to above. To this end, the step illustrated in Fig. 5 is carried out, said step consisting 60 in forming a course *d* in the same manner as that described in connection with Fig. 2 and the course *c* except that the loops in the course *d* are cast off in the even numbered wales, to permit the odd numbered loops in 65 said course *c* to be stretched and enlarged

at the expense of the even numbered loops in said course. A fourth course *e* is now formed in the same manner as the course *c* in order to permit the stretching of the loops in the even numbered wales in the course *d*. 70

It will be evident that in the operations above indicated the steps (1) casting off the alternate loops of a previous course on to a new loop and (2) stretching the intervening loops to take some of the yarn from the freely cast off loops may be carried out either simultaneously, as described, or successively, as by first performing the first step with respect to the wales 1, 3, 5, 7, etc., and thereafter performing the second 75 operation with respect to the wales 2, 4, 6, etc.; but I usually prefer to carry out the first step by operating the instruments casting off the loops of the course *c* at wales 1, 3, 5, etc., in succession, operating the remaining instruments in the same order, and thereafter; that is to say, in the case of the wales 2, 4, etc. I perform the operations respectively after the preceding operations in wales 3, 5, etc. In this way the first operation, which must be completed before the second operation begins, may be being performed at one part of the fabric, while the second operation is being performed at another part of the fabric; and when I state 80 that the operations are successively performed I merely mean to imply that they are performed in succession to each other with respect to neighboring or nearby wales. Ordinarily it will be sufficient to operate 85 the instruments, when the fabric is at the stage indicated in Fig. 2, so that at the wales 1 and 3 the loops of the course *a* have been cast off before the stretching operation in wale 2 is begun, and before the loop pulling 90 or knitting operation for wale 2 and course *c* is performed. It will also be apparent that having fed a course of yarn such as the course *c* in Fig. 2 and then having manipulated the loops of course *b* as shown 95 in Fig. 3 to produce the result shown in Fig. 4, that it is immaterial whether the completion of the operation, shown in Fig. 5 by knitting the loops of the even numbered wales for the course *c* through the now elongated loops of course *d* is performed simultaneously with, or in succession to, the 100 operation of elongating said loops.

A marked advantage of my method of knitting lies in my ability to produce by its 105 practice a fabric having some stitches or meshes much smaller than could otherwise be formed by the same instruments, resulting in a balanced structure having large and small stitches so grouped that subsequent 110 wear and strain will not distort the fabric, although it results in a lighter fabric than is possible where all the stitches are of uniform length. This is due to the fact that the small stitches are so tightly drawn that 115 120 125 130

they serve to maintain a requisite firmness, while on the other hand the large stitches are so large that they not only tend to make the fabric more porous, but materially reduce the weight per unit of the surface.

It will be understood that the drawings are diagrams only, failing to show, for the sake of clearness, the true relative size of the long and short loops, or their proportions with respect to the diameter of the

yarn.

Having described my invention what I claim and desire to secure by Letters Patent is:

1. The method of knitting a fabric having all of its loops drawn toward the same face, and presenting regular alternations in both the needle wales and yarn courses of large and small loops, which consists in knitting a course by successively first knitting in each of certain wales only a normally sized loop, and thereafter drawing upon the loop of a previous course in each of said certain wales whereby said loops of said previous course are decreased in size; and in thereafter repeating said operations in a subsequent course in a different order of wales.

2. The method of knitting a fabric having recurrent long and short loops drawn to the same face of the fabric, which consists in knitting a first course, in then knitting loops in certain wales only of a second course, whereby the loops in said wales of the first course are freed from the instruments upon which they were formed, in then drawing upon the yarn and knitting at the location of the neighboring wales, to shorten the freed loops of said first course in said certain wales, and in then repeating the operation.

3. The method of knitting a fabric having recurrent long and short loops drawn to the same face of the fabric, which consists in knitting a first course, in then knitting loops in certain wales only of a second course, whereby the loops in said wales of the first course are freed from the instruments upon which they were formed, in then drawing upon the yarn and knitting at the location of the neighboring wales, to shorten the knit loops of said first course in said certain wales, and in then repeating the operation, in a subsequent course, in a relatively different order of wales.

4. The art of knitting fabrics having a recurrent series of long and short loops drawn to the same face of the fabric, which consists in first knitting in a course of successively formed loops and as a loop of normal size, that loop which is thereafter to become a small loop, the operation including the casting of said loop on to the following loop, and then subsequently drawing excessively upon the yarn and forming knit loops

in wales preceding in the direction of formation of said short-loop wale, whereby the previous course loops in said preceding wales take part of the yarn from and shorten the first formed loops; in repeating all of said operations in successive wales to form a course of loops, and in subsequently forming another course by repeating the operation.

5. The method of knitting a fabric having recurrent short and long loops, which consists in knitting a course of yarn through a previous course, all the loops being drawn to the same face of the fabric, in subsequently completing the operation by knitting loops of a following course in certain predetermined wales only, whereby some only of the loops of the first mentioned course are completed and cast off as stitches of a normal size, and in then drawing upon the yarn of the remaining loops of the first mentioned course to reduce in size said completed stitches, and thereafter knitting the remaining loops of said following course.

6. The method of knitting a fabric having recurrent short and long loops, which consists in knitting a course of yarn through a previous course, in subsequently completing the operation by knitting loops of a following course in certain predetermined wales only, whereby some only of the loops of the first mentioned course are completed and cast off as stitches of a normal size, and in then drawing upon the yarn of the remaining loops of the first mentioned course to reduce in size said completed stitches and thereafter knitting, toward the same face of the fabric, the remaining loops of said following course.

7. The art of knitting fabrics having recurrent series of long and short loops which consists in first knitting a course including those loops which are thereafter to become short loops, the operation comprising the casting on to the following loop of a new course of each of said loops, in subsequently drawing excessively upon, and then knitting loops of said new course through the loops of the wales adjacent to the short loop wales, whereby said drawn-upon loops take part of their yarn from and shorten the first-mentioned loops; and in repeating all of said operations at different wales in successive courses to form recurrent long and short loops in each of the wales.

8. The art of knitting a fabric upon a series of instruments, which consists in knitting, by forming loops and casting them off upon loops of a following course at each of certain alternate instruments of the series only, in succession in one direction, and in operating upon the yarn at each instrument preceding in said direction those first operated upon, after the close of the first operation, to draw upon the cast-off stitch or loop,

to reduce its size below normal, and in thereafter operating upon the yarn at the same instruments to form knit loops.

9. The art of knitting a fabric having long and short loops in recurring wales, which consists in knitting first a course having normal loops in each wale which is to present a short stitch and then drawing upon the yarn at the location of the intervening loops to elongate them to an extent in excess of the draft necessary for knitting another course, and to shorten said normal loops, prior to knitting through said long loops, and then knitting other courses.
10. The art of knitting a fabric having long and short loops in recurring wales, and in a different order in recurring courses, which consists in knitting first a course hav-

ing normal loops in each wale which is to present a short stitch of said course and 20 then drawing upon the yarn at an intervening loop to elongate said loop to an extent in excess of the draft necessary for knitting another loop through said intervening loop and thereby to shorten the previously 25 formed stitches, prior to knitting through said elongated loop, and in then repeating the said operations for another course, but in a different order of wales.

In testimony whereof I have signed my 30 name in the presence of the subscribing witnesses.

ROBERT W. SCOTT.
